UNITED STATES PATENT OFFICE.

HUGO DORNSIEF, OF RADEVORMWALD, GERMANY.

PENCIL SHARPENER.

Application filed November 1, 1922. Serial No. 598,368.

To all whom it may concern:

Be it known that I, Hugo Dornseif, a citizen of Germany, residing at Radevormwald, Rheinland, Germany, have invented 5 certain new and useful Improvements in Pencil Sharpeners, of which the following is a specification.

My invention has reference to a pencil sharpener which may be carried in the 10 pocket and is provided with a supply of exchangeable knives, and with this end in view provision is made for connecting with the pencil sharpener a suitable container for the reception of a supply of exchangeable knives, 15 so as to enable the operator to always have a sharpened fresh knife at his disposal in case of need and to do away with the tedious re-grinding of the knives.

The invention is particularly adapted for 20 that kind of pencil sharpener which comprises a substantially prismatic body with conical aperture, and in accordance with my invention the container for the knives may be formed in the most simple manner by a 25 recessed part of the prismatic body laterally arranged with relation to the conical aperture. This recess or cavity is preferably arranged upon the side of the device opposite to the operating knife and is preferably arranged 30 in such a manner as to substantially register with the recess for the accommodation of the operating knife on the opposite side of the body portion of the device. By this means the advantage is obtained 35 that the operating blade and the supply blades may be retained by the same screw which passes through a transverse aperture of the body portion of the device. The arrangement may be such that the recessed 40 portion on both sides of the body may be of the same size so that they may be manufactured by means of one and the same tool or the like. The fastening screw is preferably inserted from the side of the operating knife 45 and is passed through the transverse bore of the body portion and into a preferably inwardly threaded bore of the cover for the cavity in which the supply blades are housed. By this means one is enabled to dispense 50 with the necessity of providing screw threads in the body portion of the device which is ordinarily made of some soft metal, such as an aluminium alloy or the like, such threads not being very durable on account of 55 the softness of the metal.

An embodiment of the principles of my invention is shown on the accompanying drawing by way of example—

In Fig. 1 in front view,

In Fig. 2 in rear view, and

In Fig. 3 in plan view.

Fig. 4 is a rear view of the pencil sharpener with a knife container in the open position.

Fig. 5 is a cross-sectional view on the line 5—5 of Fig. 1 and

Fig. 6 is a longitudinal section on the line 6—6 of Fig. 1.

As shown on the drawings, the pencil sharpener comprises a substantially prismatic body portion *a* of some light metal, an aluminium alloy for example, and is provided with a lengthwise extending, eccentrically arranged conical hole *b* and with a longitudinal slot *c*. Upon the front side of the body portion *a* a recess *d* is provided in which by means of a screw *f* the knife *g* is removably secured, the cutting edge of which projects through the slot *c* into the conical hole *b*.

Upon the side of the body portion opposite the knife *g*, that is to say, on the rear side of the body *a* a recess *h* is provided of the same configuration, but of greater depth than the recess *d* and registering therewith. The cavity or recess *h* upon the rear-side of the body is provided with a covering lid *i* and constitutes a container for the reception of a plurality, for instance of two supply knives *k*. These knives are retained in position according to my invention by the fastening screw *f* of the operating knife *g*. For this purpose the screw *f* is passed through a transverse hole *m* in the body *a* and through the ordinary fastening holes in the knives *g*, *k*, *k* and enters into the internally threaded bore *n* of the lid *i*. The upper end of the lid *i* is inwardly curved at *i'* so as to also provide for the closing of the recess *h* at the front portion of the body *a*. For the purpose of facilitating the removal of the cover or lid *i* the body *a* at its upper front portion is provided with a small depression *o*.

On its longitudinal side the body *a* may be provided in a well known manner with sockets *p*, *p* for the purpose of facilitating the manipulation and the grasping or turning of the pencil sharpener.

If the blade *g* has become dull, the screw *f*

is loosened, thereby simultaneously releasing the blade *g* and the cover *i* of the recess *h*. The knife *g* may then be exchanged for a fresh knife taken from the container *h*, 5 while the dull knife may be placed into said container, whereupon, after the insertion of the cover *i*, the screw *f* may be reinserted and the operating knife may be locked in position and the container *h* for the supply 10 blades is closed.

It is evident that the invention is susceptible of various modifications and variations to suit existing conditions and the convenience of the user. Thus, for instance, the 15 container for the exchangeable supply blades may comprise a lateral recess in the body portion which is closed by the sliding cover. The container for the supply knives may, with a suitable thickness of the body 20 portion of the device, be made of such depth that it becomes adapted for the reception of more than two knives. In the form of construction shown by way of example and by the use of only two supply blades there is 25 the advantage that the pencil sharpener, notwithstanding the provision of the additional container, need not be of larger size than the ordinary pencil sharpener which consists of a substantially prismatic body with conical 30 apertures.

I claim:

1. Pencil sharpener comprising a body portion with an axial opening to receive a pencil to be sharpened, a blade mounted on one side of said body portion with its cutting edge projecting into said opening, a cavity in the opposite side of said body portion in register with said blade, a cover for said cavity and a headed bolt with threaded end extending through a hole in said blade, 35 a plain transverse boring of said body portion and through said cavity into a threaded hole in said cover so as to retain it on said cavity.
2. Pencil sharpener comprising a body 45 portion with an axial opening to receive a pencil to be sharpened, a blade mounted on one side of said body portion with its cutting edge projecting into said opening, a cavity in the opposite side of said body portion in register with said blade, an angular cover for said cavity and a headed bolt with threaded end extending through a hole in 50 said blade, a plain transverse boring of said body portion and through said cavity into a threaded hole in said cover so as to retain it on said cavity.

In testimony whereof I affix my signature.

HUGO DORNSEIF.
